CLAIM

The ornamental design for a key for a filament feed tube, as shown and described.

DESCRIPTION

FIG. 1 is a perspective view of a key for a filament feed;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines shown in the drawings are included for purposes of illustrating portions of the key for a filament feed tube and form no part of the claimed design.

1 Claim, 5 Drawing Sheets(56)
